Friedrich LLP(57) **CLAIM**I claim the ornamental design for a cutter, as shown and
described.**DESCRIPTION**FIG. 1 is a perspective view of a cutter showing my new
design.

FIG. 2 is a front view of the cutter of FIG. 1.

FIG. 3 is a rear view of the cutter of FIG. 1.

FIG. 4 is a right side view of the cutter of FIG. 1.

FIG. 5 is a left side view of the cutter of FIG. 1.

FIG. 6 is a top view of the cutter of FIG. 1; and,

FIG. 7 is a bottom view of the cutter of FIG. 1.

The dot-dashed lines shown in the drawings represent the
boundary lines of the cutter and form no part of the claimed
design. The evenly spaced broken lines show portions of the
cutter that form no part of the claimed design.**1 Claim, 4 Drawing Sheets**| (56)	References Cited
